COMBINED MOTION PICTURE PROJECTOR AND CARRYING CASE

Dianne B. Ainslie and Andrew V. McClare, Rochester,
N.Y., assignors to Eastman Kodak Company, Rochester,
N.Y., a corporation of New Jersey

Filed May 29, 1967, Ser. No. 7,294

Term of patent 14 years

(Cl. D61—1)

FIG. 2

FIG. 1

FIG.5

FIG.6

FIG. 7

FIG. 1 is a side elevational view of a combined motion picture projector and carrying case, showing our new design with the side cover plate attached;

FIG. 2 is a front elevational view;

FIG. 3 is an opposite side elevational view;

FIG. 4 is a rear elevational view;

FIG. 5 is a top plan view;

FIG. 6 is a bottom plan view; and

FIG. 7 is a perspective view with the side cover plate visible in FIG. 1 removed.

We claim:

The ornamental design for a combined motion picture projector and carrying case, as shown.
